UNITED STATES PATENT OFFICE.

THEODORE VARNEY, OF PITTSBURG, PENNSYLVANIA, ASSIGNOR TO WESTINGHOUSE ELECTRIC & MANUFACTURING COMPANY, A CORPORATION OF PENNSYLVANIA.

STRAIN-INSULATOR FOR ELECTRIC LINES.

No. 861,149.

Specification of Letters Patent.

Patented July 23, 1907.

Application filed June 4, 1906. Serial No. 320,139.

To all whom it may concern:

Be it known that I, THEODORE VARNEY, a citizen of the United States, and a resident of Pittsburg, in the county of Allegheny and State of Pennsylvania, have 5 invented a new and useful Improvement in Strain-Insulators for Electric Lines, of which the following is a specification.

My invention relates to strain insulators for electric lines and it has for its object to provide a device of this 10 character that shall be specially compact and durable in construction and capable of withstanding strains incident to the use of high voltages.

The single figure of the accompanying drawing is a 15 sectional view of a strain insulator constructed in accordance with my invention, and reference may now be had to this figure.

The strain insulator which is illustrated, comprises a relatively short metal tube 1, metal end caps 2 and 3 that are screw-threaded onto the ends of the tube 1, 20 taper bolt heads or plugs 4 and 5 which are fitted into suitable holes in the end caps, and means for insulating the plugs or bolt heads from the caps.

The caps 2 and 3 are preferably provided with taper holes 6 and 7 and the material of which the caps are constructed is relatively thick, adjacent to the holes, so that the taper plugs or bolt heads 4 and 5, which are fitted substantially into the middle of taper tubes 8 and 9 of hard insulating material, such as micanite, may more readily and securely be seated therein.

30 The taper plugs or bolt heads 4 and 5 are provided with stems or bolts 10 and 11 which extend outwardly beyond the extremities of the tubes 8 and 9 and are screw-threaded to engage strain loops 12 and 13. The cap 3 is provided with one or more relatively small 35 holes 14, which are located between the inner surface of the tube 1 and the hole 7 in which the taper plug 5 is located. The tapers at either end of the assembled structure converge outwardly so that when forces in tension are applied to the strain loops 12 and 13, the taper plugs 4 and 5 are drawn firmly into position.

When the parts already described have been assembled, the interior of the tube 1 is filled with a suitable 45 hot liquid insulating compound which is poured in through the openings 14, then the entire structure between strain loops 12 and 13 is enveloped in a casing 15 of molded insulation which may be applied under heavy pressure in a well known manner. The pressure applied in molding the casing in position is transmitted to the insulating compound in the interior of the tube so 50 that the entire structure becomes very hard and rigid.

During the molding process, the strain loops 12 and 13 will probably be removed and replaced by cylindrical

rods of substantially the same diameter as the bolt heads or plugs 4 and 5 so that the pressure may be entirely equalized inside and outside the tube 1 except for a 55 pressure tending to separate the two bolt heads or plugs 4 and 5.

The taper tubes 8 and 9 are made of sufficient length so that a considerable surface leakage distance is provided between the electrically separated parts and 60 their insulating properties are retained since the casing 15 of molded insulation completely seals them from the weather. A further advantage of the strain insulator of my present invention lies in the fact that any tendency for the tapered plugs or bolt heads to become 65 loosened or unseated when the device is suddenly released from mechanical tension is prevented by reason of the solid mass of insulating compound which has hardened under pressure between the inner ends of the 70 plugs or bolt heads.

I desire that only such limitations be imposed as are indicated in the appended claims since variations in size and arrangement of details may be effected within the scope of my invention.

I claim as my invention:

1. A strain insulator comprising a metal tube, removable end caps therefor having taper holes, taper plugs seated in said holes and having stems or bolts projecting outwardly therefrom, and means for insulating the taper plugs from the end caps.

2. A strain insulator comprising a metal tube, end caps therefor having taper holes, taper plugs seated in said holes and having stems or bolts projecting outwardly therefrom, means for insulating the taper plugs from the end caps and strain loops removably attached to the stems or bolts.

3. A strain insulator comprising a metal tube having end caps provided with taper holes, taper tubes of insulating material seated in the holes, taper plugs seated in the taper tubes and having stems extending outwardly therefrom, and strain loops attached to the stems.

4. A strain insulator comprising a metal tube having end caps provided with taper holes, taper tubes of insulating material seated in the holes, taper plugs seated in the taper tubes and having stems extending outwardly therefrom, strain loops attached to the stems and a molded casing of insulating material which seals the conductor and extends from one strain loop to the other.

5. A strain insulator comprising a metal tube, end caps therefor having taper holes, taper plugs seated in the holes and having stems projecting outwardly therefrom, strain loops attached to the stems, and a molded casing of insulating material which seals the conductor and extends from one strain loop to the other.

6. A strain insulator comprising a metal tube, end caps screw-threaded thereon and having outwardly tapering holes, taper tubes of insulating material seated in the holes and bolts projecting from the tubes and having taper heads seated in the tubes.

7. A strain insulator comprising a metal tube, end caps screw-threaded thereon and having outwardly tapering

holes, taper tubes of insulating material seated in the holes, bolts projecting from the tubes, and strain loops attached to the ends of the bolts.

8. A strain insulator comprising a metal tube, end caps screw-threaded thereon and having outwardly tapering holes, taper tubes of insulating material seated in the holes, bolts projecting from the tubes, strain loops attached to the ends of the bolts, and a casing of molded insulation that seals the structure and extends from one strain loop to the other.

9. A strain insulator comprising a metal tube, end caps therefor having taper holes, taper plugs seated in the holes and having stems projecting outwardly therefrom, strain loops attached to the stems, an insulating compound which fills the space in the metal tube between the plugs, and a molded casing of insulating material which seals the structure and extends from one strain loop to the other.

10. A strain insulator comprising a metal tube having end caps provided with taper holes, taper tubes of insulating material seated in the holes, taper plugs seated in the

taper tubes and having stems extending outwardly therefrom, strain loops attached to the stems, an insulating compound which fills the space in the metal tube between the plugs, and a molded casing of insulating material which seals the structure and extends from one strain loop to the other.

11. A strain insulator comprising a metal tube, caps therefor having taper holes, taper plugs seated in the holes and having stems projecting outwardly therefrom, strain loops attached to the stems, an insulating medium within the tube which exerts a pressure tending to separate the plugs, and a molded casing of insulating material which seals the structure and extends from one strain loop to the other.

In testimony whereof, I have hereunto subscribed my name this 31st day of May, 1906.

THEODORE VARNEY.
